CLAIM

We claim the ornamental design for a model vehicle bumper, as shown and described.

DESCRIPTION

FIG. 1 is an upper, right, front perspective view of a model vehicle bumper showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof; and,

FIG. 8 is a lower, left, front perspective view of the model vehicle bumper.

In the drawings, the broken lines illustrate portions of the model vehicle bumper that form no part of the claimed design.
